UNITED STATES PATENT OFFICE.

CLARENCE P. BYRNES, OF SEWICKLEY, PENNSYLVANIA.

SPRING-CUSHION DEVICE.

1,162,283.

Specification of Letters Patent. Patented Nov. 30, 1915.

Application filed December 5, 1907. Serial No. 405,199.

To all whom it may concern:

Be it known that I, CLARENCE P. BYRNES, of Sewickley, in the county of Allegheny and State of Pennsylvania, have invented a 5 new and useful Spring-Cushion Device, of which the following is a full, clear, and exact description, reference being had to the accompanying drawings, forming part of this specification, in which—

10 Figure 1 is a horizontal section of a tandem draft gear, constructed in accordance with my invention; and Fig. 2 is a sectional side elevation of the same.

15 My invention relates to the class of springs set forth in my Patent, Number 743,689, dated November 10, 1903.

20 The object of the invention is to increase the resistance of the spring and avoid liability of breaking, bending or uncoiling of the thinner end portion or portions of the spring, which are tapered down from the 25 full cross section, or cut off at full section. In the externally coiled springs, such as shown in the present drawings, it has been found that under extreme loads of between 200,000 and 300,000 pounds, the end portion of the spring at one end tends to be forced 30 downwardly and outwardly out of its normal position, thus starting to uncoil or distort the true shape of the spring. This 35 may happen whether the spring is provided with a tapered end or cut off at full cross section. My invention is designed to prevent this bending, breaking or unwinding 40 of the partial cut coil and consists in holding this end coil in its proper position by a pocket follower.

45 In the drawings, in which I have shown the invention as applied to a tandem gear, 40 2 and 3 represent tandem gear springs. Of these springs, 2 shows approximately the section of my prior Patent, Number 743,689, while 3 shows a changed section, giving the same effect but with a double-headed cross 50 section, making the section uniform at both ends and reversible. This section also tends to stiffen the spring and increase its resistance during the stroke. With this spring, I 55 preferably employ follower plates 4, 5, 6 and 7, these plates having pockets, preferably of annular form, to receive the partial end coils of the springs. These annular pockets may be formed by recessing the follower or by the use of projecting lips, or 60 providing the follower with any other device or mechanism which acts as retainer for

the end coil, to prevent its distortion. I have shown these followers as duplicates of each other, and this is the preferred form, since only one type needs to be kept in stock. 60 The inner projections 8 of these followers, which fit within the end coils of the springs, are not essential, although I prefer to use them. In fact, the pocket or retaining device for the end coil is only necessary on that 65 end of the spring having the partial coil which tends to be forced outwardly and downwardly from the next coil, as extreme pressure is applied; in the case of outside winding as here shown. The pocket may 70 therefore have two retaining walls—internal or external—or one retaining wall which is external at the end where the coil tends to force outwardly. The followers may have an external retaining wall or 75 pocket at one end, and an internal pocket at the other end, but this would require two types of follower, and would be objectionable for that reason.

80 In the device, as shown, 9 is the usual strap and 10 the check plates having stops 11 for the followers. In order to make the springs of the proper diameter relative to the strap 9 and space between the draft sills, I preferably recess the followers at opposite sides, as shown at 12, to allow the strap to pass within these slots. The followers are thus enabled to coact in 85 the usual manner with the stops, while at the same time, the spring may be made of 90 the desirable diameter, according to M. C. B. practice.

95 13 represents the draft sills, and 14 the shank of the coupler, to which the strap is secured in the usual manner. In the form shown, a central block 15 is secured to the opposite sides of the strap 9, between the followers 5 and 6. This gives simultaneous movement to the same amount upon both 100 springs, giving each spring the full stroke in the usual manner of the ordinary draft rigging springs.

105 The advantages of my invention result from the greater resistance obtained and the doing away with the liability of un winding, breaking or bending down the partial end coil of the spring. By employing a retainer for this partial end coil, the cam operation of one coil upon the next is prevented from distorting the partial end 110 coil and starting it to unwind the spring.

Other forms of retainers for the partial

end coil may be employed. The retaining device may be employed at one or both ends, and may be either internal or external or both.

b I claim:

1. The combination with a helical spring having its coils arranged to give cam action upon each other around different parts of their circumference, and an end plate having a surrounding recess of a shape corresponding to the normal cross section of the spring and arranged to prevent undue distortion of the partial end coil in any position thereof, substantially as described.
- 10 2. The combination with a helical spring

having its coils arranged to give cam action upon each other around their circumference, of end plates having surrounding recesses corresponding to the normal cross section of the spring, each of said recesses being 20 arranged to prevent undue distortion of the partial end coils in any position of the same within the recesses, substantially as described.

In testimony whereof, I have hereunto set 25 my hand.

CLARENCE P. BYRNES.
